UNITED STATES PATENT OFFICE

FRIEDA C. NEUHAUS, OF LOS ANGELES, CALIFORNIA

RESTAURANT BUILDING

Application filed June 10, 1929. Serial No. 369,540.

My invention relates to a building that is especially designed for use as a restaurant or café, and the principal object of my invention is to provide a building that has the shape or configuration of a cookstove or range, said building being of sufficient size to be used as a restaurant or café, and further, to provide the stove with a base upon which is arranged for movement, figures or images that are designed to represent cooks, waiters and other persons usually employed in the preparation and serving of food refreshments in restaurants and the like and which figures or images are mounted so that they traverse predetermined paths that lead into the main door of the building and through the room in which patrons are served, thereby attracting the attention of passersby and affording interest and amusement to patrons of the café or restaurant.

With the foregoing and other objects in view, my invention consists in certain novel features of construction and arrangement of parts that will hereinafter be more fully described and claimed and illustrated in the accompanying drawings, in which:

Fig. 1 is a perspective view of a restaurant building constructed in accordance with my invention.

Fig. 2 is a horizontal section taken approximately on the line 2—2 of Fig. 1.

Fig. 3 is an enlarged vertical section taken on the line 3—3 of Fig. 2.

Referring by numerals to the accompanying drawings, 10 designates a base that may be formed of any suitable material, for instance, wood or combination of wood and metal covered with cement or stucco, and rising from said base are four walls 11 arranged so as to provide a substantially rectangular room or chamber and the outer surfaces of these walls may be provided with doors, windows and the like that are shaped to simulate the doors and openings in an ordinary cookstove or range.

The front wall of the building is provided with a relatively large centrally arranged doorway 12 that has the general shape of the oven door of a cookstove and arranged in the upper left hand corner of the front wall 11 is a window or opening 13 which cor-

responds to the opening that is formed at the forward end of the fire box in a cookstove or range.

In order to attract attention and add interest in the building I prefer to arrange a section of glass in the opening 13 and to mount colored lights within the building behind said window to represent flames.

Further to give the effect of flames through the opening 13 a series of pieces of red and yellow colored fabric may be secured within the building just below the opening 13 and by means of a blast of air directed upwardly these sections of fabric may be caused to wave after the manner of ascending flames.

The top 14 of the building may be painted or shaped to represent the ordinary stove or range top and surrounding the top and spaced a short distance therefrom, a rail 15, similar to the rail that is positioned on a range or cookstove and which serves as a support for various cooking utensils and the like.

Projecting upwardly from one end of the top 14 of the building is a tubular member 16 that is intended to represent a stove pipe or chimney. While the café or restaurant is in operation steam may be permitted to discharge from the pipe or chimney 16, thus giving the appearance of smoke and which adds to the interest of the building.

Arranged on the base, within the building, are tables 17 for the accommodation of the patrons or guests and also arranged within the building, preferably at one end thereof, are ranges or tables 18 for the accommodation of the employees that prepare and serve the food and refreshments.

Formed in that portion of the base 10 that projects beyond the walls of the building are slots 19 and these slots extend through the base from the doorway 12 to the rear portion of said base outside the chamber enclosed by the walls 11 and arranged immediately beneath these slots are endless chains 20 that pass around sprocket wheels 21, which latter are suitably supported to rotate in horizontal planes just below the top of the base 10.

Between the sprocket wheels 21 the chains 20 are supported by horizontally disposed

rollers 22 that are mounted on shafts 23 beneath the base 10. (See Fig. 3).

Chains 20 are driven by means of a motor 24 located on the rear portion of base 10 and which motor has suitable driving connections 25 with two of the sprocket wheels 21. Secured to the chains 20 at suitable distances apart are the lower ends of upright rods 26 which project through the slots 19 and mounted on the upper portions of said rods are figures or images 27 that simulate cooks, waiters and other employees that are usually engaged in the preparation and serving of food and refreshments in cafés and restaurants.

Secured to and depending from those portions of the figures or images that represent the feet are suitable rollers 28, preferably of the caster type, which ride directly on the top surface of the base 10.

While the café or restaurant is open for service motor 24 is operated, thereby driving chains 20 and the figures or images 27 connected thereto will move over the top of the base directly above the slots 19 and during such movement said figures or images will pass across the ends of the base, thence inwardly toward the door opening 12 and thence through said door opening and rearwardly through the chamber within the building and which is occupied by the tables 17 and the moving figures will attract attention of passersby as well as creating interest and amusement for the patrons of the café or restaurant.

As shown in Fig. 1 of the drawing, there may be arranged on top of the stove or range large objects formed of sheet metal or papier mâché and which are shaped to represent various cooking utensils such as a roasting pan, a stewing pan, a coffee pot or the like.

Thus it will be seen that I have provided a building that is especially designed for use as a café or restaurant, which building is shaped to represent a cooking stove or range and said building includes moving figures or images that represent persons engaged in preparing and serving food and refreshments to the patrons of the restaurant.

It will be understood that minor changes in the size, form and construction of the various parts of my improved restaurant building may be made and substituted for those herein shown and described without departing from the spirit of my invention, the scope of which is set forth in the appended claims.

I claim as my invention:

1. In a restaurant building, a base provided with a door opening, the top of the base being provided with two separate endless slots, portions of which pass through the door opening and that portion of the base to the rear of said door opening, sprocket wheels journaled beneath the base adjacent to the slots therein, a sprocket chain mounted for operation on each set of sprocket wheels,

images mounted for movement on top of the base, connections between said images and the sprocket chains, a motor arranged on the base between the two sprocket chains and driving connections between said motor and two of the sprocket wheels.

2. In a restaurant building, a base provided with a door opening, the top of the base being provided with two separate endless slots, portions of which pass through the door opening and that portion of the base to the rear of said door opening, sprocket wheels journaled beneath the base adjacent to the slots therein, a sprocket chain mounted for operation on each set of sprocket wheels, images mounted for movement on top of the base, connections between said images and the sprocket chains, a motor arranged on the base between the two sprocket chains, driving connections between said motor and two of the sprocket wheels and rolling supports for said sprocket chains arranged within the base beneath the slots therein.

In testimony whereof I affix my signature.

FRIEDA C. NEUHAUS.
